UNITED STATES PATENT OFFICE.

FRANK C. HAASSLER, OF BROOKLYN, NEW YORK.

FIRE INDICATING AND EXTINGUISHING SYSTEM.

1,189,686.

Specification of Letters Patent. Patented July 4, 1916.

Application filed April 13, 1914. Serial No. 831,592.

To all whom it may concern:

Be it known that I, FRANK C. HAASSLER, a citizen of the United States, and resident of Brooklyn, in the county of Kings and State of New York, have invented certain new and useful Improvements in Fire Indicating and Extinguishing Systems, of which the following is a specification.

My invention relates to a fire indicating and extinguishing system and the object is to arrange the operation of the system so that it can be readily directed or used, whenever desirable, for either disinfecting and ventilating a ship or for signaling and extinguishing a fire thereon, without the slightest material change to the principle of operation, respecting the mechanical installation, which embodies cheapness, neatness and practicability.

Referring to the drawing—Figure 1, is an elevation of a ship partly in section showing my system installed therein; Fig. 2 is a plan of same; Fig. 3, is a plan sectional of the hold of the ship, showing the arrangement of the stand pipes and their sprinklers. Fig. 4 is a sectional elevation of one end of the ship enlarged showing my system installed within the inclosure thereon. Fig. 5, is a similar view to Fig. 4, showing my system installed on the outer deck and the decks below the same of the ship. Fig. 6, is a fragmentary plan view of part of the supply pipes, showing the permanent Y connection with the stand pipes. Fig. 7 is a vertical sectional view of part of the ship showing how the pumps are connected to the supply pipes. Fig. 8 is an enlarged fragmentary view showing part of a stand pipe, with mercury cup in section, and the electric bell attached.

Numeral 2 designates the ship; the shape and size thereof being immaterial. The ship has a hold 3, decks 4 and 5 and outer deck 6 on which is placed the housing 7. The hold and decks 4—5 are partitioned off into compartments 14, 15 and 16 by the divisions 12. The number of decks and compartments is immaterial, being governed by the size of the ship.

To simplify the description of my system, I will confine it to one compartment 14, within which I place (on both sides of the ship) the standpipes 17 and 18, intended to communicate or connect the hold 3, with the housing 7. (See Figs. 1—4). If the compartment is large there may be more than

two stand pipes to the hold—but not less than two. The decks 4 and 5 likewise have two or more stand pipes 19—20 see Fig. 1. The compartments 15 and 16 have also two or more stand pipes 23 for the hold and decks thereof. The hold and deck ends of all these stand pipes have perforated branch pipes 24, serving as sprinklers, and in turn these pipes have also perforated branches, see Fig. 2. The upper ends of all these stand pipes are provided with opening and closing, valves 26, and also with gas or smoke escaping outlets 25, see Fig. 4. Within the housing 7, preferably on the floor thereof are laid the two supply pipes 27, 28, see Fig. 4, in close proximity to the stand pipes, so that each of same can be permanently connected to the said supply pipes by the Y coupling 40, see Figs. 1, 2, 4, 6. Each of these couplings 40, is closed and open to the supply pipes 27, 28 by the valves 41, 44 and also provided with pet cocks 48. All of the supply pipes have compartment cut off valves 42. Supply pipe 27, is adapted to convey water through the system. Supply pipe 28 is adapted to convey steam through the system. The water supply pipe is connected with the pumps 9 by pipes 31 which have valves 70—71 for directing the water to either or both sides of the ship, whenever required during the operating of the system. The steam supply pipe 28 is connected to the boiler 8 by pipe 30, which can also have similar directing valves as the water pipes to convey the steam to any part of the ship for the system.

The system is started in operation for ventilating and announcing a fire on a ship, by first closing all the Y coupling valves 41, 44 and opening all the stand pipe valves 26, thus permitting all the stand pipes to have free passage from hold and decks to the air. Now should combustible gases fill the hold or decks of the ship, it would naturally enter the sprinklers 24 and branches, and find its way into the stand pipes, up same, and out through the outlets 25 thereof into the air, and thereby preventing spontaneous combustion on board the ship. But in place of the gases, if smoke should appear rushing out of the outlets 25, of stand pipes, it would be a signal that there is a fire in the hold or decks of the ship. If, for instance, in the hold 3, it will come out of the hold stand pipes 17—18; if in deck 4, then out

of pipes 19-20; and if in deck 5, then out of pipes 21-22; thus locating the origin of the fire instantly. When located, instantly close the valves 26 and (if 5 water is used to extinguish the fire) open the coupling valve 44, charge supply pipe 27 with water and allow its force to rush down the smoke announcing stand pipes, into and through their sprinklers, upon the 10 fire until extinguished, which is determined by shutting off the water from one of the stand pipes and opening its valve 26, and if no smoke appears then shut off the water entirely and set the system again. But if 15 smoke again appears then close valve 26, open valve 44 and continue exhausting by water. If the fire is within a given compartment, then the compartment valve 42 of the water supply pipe 27, is closed so as 20 to confine the water to that compartment.

I do not limit myself to the smoke, alone, coming out of the outlets 25 of the stand pipes to announce the fire, as I intend to use a bell to give the signal principally at night. 25 To do this I provide each stand pipe with a mercury cup 50 which is provided with an electrical contact float 56, which when raised by reason of the hot smoke expanding the mercury 53 will contact with cover 58. Now 30 as both float 56 and cover 54 are electrically contacted by wires 55 to the bell 52, therefore, when the contact takes place, it will instantly ring the bell. In some cases I supersede the bell with electric lights, or 35 may use both together.

Certain cargoes do not permit the use of water to extinguish them when on fire. In that case I use steam; and to do this by my system simply open the valve 41, on the Y 40 coupling 40 and allow the steam in supply pipe 28 to travel through the stand pipes in the same manner as the heretofore described water.

As some compartments may have cargoes 45 where water can be used to extinguish the fire, and others where water cannot be used, I can by the Y couplings 40, supply the system with water for one compartment and steam for another without interrupting the 50 operation of the system.

To use my system for forcing extinguishing gases into the compartments of ships, simply connect the supply pipes 27 or 28 (in any suitable manner) with the source of 55 supply of the gases.

I am aware that I can disinfect a ship by my system by simply connecting the pipes 27 or 28 with the source of supply of the disinfectant.

60 In case of storms this system is better manipulated, as shown in Figs. 1-4, within the housing 7. Especially is this so with freighters which will not allow the supply pipes 27, 28 to be laid on the below decks 65 4-5. But when these pipes can be laid on

the below decks 4-5 as shown in Fig. 5, then the upper Y coupling 40 can be placed on the outer deck 6, and below decks 4-5, see Fig. 5. The only difference in this method is that the stand pipes do not have the outlets 25; 70 but utilize the valves 26 as a smoke or gas announcer. The advantage of the style shown in Fig. 5, (the exposed style), is that a fire can be fought more closely at its origin. I can run the sprinklers 24 below 75 the beams and close to the horizontal flange, see Fig. 4, or below same see Fig. 5; and the supply pipes can run under the flooring.

To ascertain if the stand pipes are receiving their supply of water, or steam or gas 80 from the supply pipes, simply open any one of the pet cocks 48 on the coupling 40. If water is forced out of the pet cocks then it is certain that that supply pipe is discharging water into stand pipes. The same is 85 the case with the steam or gas supply pipe. But if the pet cocks should not discharge water or gas or steam when open, then it is known that the supply is defective in operation. 90

Whenever necessary the outlets 25 of the stand pipes are each provided with means for preventing the sea washing into the said stand pipes in time of storms. When the outer deck requires flushing or for temporary fires, attach a hose to the supply pipe at 54, then charge that pipe with water and use same for flushing or extinguishing the fire. 95

I do not limit myself to the mercury cup 100 as a thermostat arrangement may be used. The supply pipes, couplings and stand pipes below decks, as in Fig. 5, can be suitably housed or inclosed.

This system can be used for buildings, &c., 105 without changing the principle. When the supply pipes are laid on the lower decks then the pump supply pipe 31 is provided with cut off valves 90 to prevent the water going beyond the deck used—same with 110 steam pipes.

What I claim:

1. The herein described combined fire indicating and fire extinguishing system for ships, comprising jointly stand pipes adapted to extend from the upper deck of said ship down and into the hold and intermediate decks thereof, each of said stand pipes provided with an opening and closing valve at its upper portion, each of said stand pipes provided at or near its upper end with an announcing or smoke escaping outlet, each of the said stand pipes provided at its lower end with perforated branch pipes adapted to convey smoke from the compartment of the ship to the said stand pipes or to distribute fire extinguishing mediums from the said stand pipes into the compartments of said ship, fire extinguishing supply pipes in pairs adapted to lie in close proximity to 125 130

said stand pipes, means for connecting said supply pipes to the said stand pipes, each consisting of a permanent Y coupling, whereby the said stand pipes can be supplied with one or both mediums for extinguishing fires at the same time, said Y couplings provided with opening and closing valves and cocks, and means for supplying the said supply pipes with the extinguishing mediums.

2. The herein described fire extinguishing and indicating system, for ships comprising a plurality of stand pipes located in the compartments of the ship, sprinkling pipes attached to said stand pipes, said stand pipes each provided with an opening and closing valve, said stand pipes provided with smoke announcing outlets controlled by said valves; supply pipes in pairs placed close to said stand pipes, means for connecting said stand pipes to said supply pipes, consisting of permanent Y couplings, said Y couplings provided with valves and cocks, said Y couplings permitting the supply pipes of one medium for extinguishing fires, to pass into the stand pipes of one or more compartments, and another medium to pass into the stand pipes of other compartments at and during the same time, and means for supplying the said supply pipes with the required extinguishing mediums.

3. The herein described fire extinguishing and indicating system, comprising a plu-

rality of stand pipes each provided with an opening and closing valve and with smoke escaping outlets controlled by said valves; perforated branch pipes attached to said stand pipes; a plurality of supply pipes located in proximity to said stand pipes and connected to said stand pipes, said supply pipes having opening and closing valves, and means for supplying an extinguishing medium to each of said supply pipes.

4. The herein described fire extinguishing and indicating system for ships, comprising a plurality of stand pipes located in the compartments of the ship; sprinkling pipes attached to said stand pipes, said stand pipes each provided with an opening and closing valve and with smoke announcing outlets controlled by said valves, means for closing said smoke announcing outlets, supply pipes in pairs placed close to said stand pipes, means for connecting said stand pipes to said supply pipes; said supply pipes having opening and closing valves, and means for supplying an extinguishing medium to each of said supply pipes.

Signed at Brooklyn in the county of Kings and State of New York this 21 day of March A. D. 1914.

FRANK C. HAASSLER.
